J. HOLLE

VALVE ACTUATING MECHANISM

Filed Aug. 1, 1921

Patented Oct. 4, 1927.

UNITED STATES PATENT OFFICE.

JOSEPH HOLLE, OF NEWARK, NEW JERSEY.

VALVE-ACTUATING MECHANISM.

Application filed August 1, 1921. Serial No. 488,750.

This invention relates to valve actuating mechanisms for explosive engines as used on automobiles and other motor vehicles.

One object of my invention is to provide a mechanism for mechanically opening and closing the valve and to use therewith spring means, operating only after the mechanism has initially closed the valve, to draw the same into fully closed position against its seat to take up any irregularities produced either in the valve or the seat or in any of the parts of the mechanism to hold the valve tightly closed, and thus enable a mechanical valve opening and closing mechanism to be effectively and efficiently used.

A further object of my invention is to provide cam means for opening and closing the valve rapidly and for holding the valve in open position a predetermined period of time longer than heretofore for permitting a greater volume of explosive mixture to be drawn into the engine cylinder, when the valve is used as an intake one, and permitting a practically complete scavaging of exhaust gases when the valve is used as an exhaust one, thereby increasing the power of the engine.

A still further object of my invention is to provide a mechanism simple in construction, having lightness of parts, and readily assembled and repaired, thus reducing the cost of manufacture and maintenance.

The invention consists further in the matters hereinafter described and more particularly set forth in the appended claims.

In the accompanying drawings—

Fig. 1 is an end view of a valve actuating mechanism constructed in accordance with my invention;

Fig. 2 is a side view of the same;

Fig. 3 is a vertical sectional view taken on line 3—3 of Fig. 1;

Fig. 4 is a horizontal sectional view taken on line 4—4 of Fig. 3;

Fig. 5 is an end view of another form of cam means; and

Fig. 6 is a side view of the same.

In the drawings, 1 indicates the cam shaft of an explosive engine, such as used in automobiles and other motor vehicles. Fixed on said shaft, as by a key 2, are two cams 3, 4, laterally spaced apart and having the contour shown in Fig. 1.

Above the cams 3, 4 is a rod or endwise movable member 5, vertically arranged in the instance shown and slidably retained in

a stationary guide bracket 6. At the lower end of said member or rod 5 is a bracket 7 integral with the rod and offset laterally from one side thereof, as shown in Fig. 2. This bracket is bifurcated and journaled in the same is a roller 8 having contact with the peripheral surface of the cam 3. Integral with the lower end of said rod 5 is an arm 9 extending downward therefrom between the cams 3 and 4, as shown in Fig. 2. The lower end of said arm 9 extends below the cam 4 and to it is secured a bifurcated bracket 10, in which is journaled a roller 11 bearing upward against the peripheral surface of the cam 4. The bracket 10 is secured to the arm 9 by a set screw 12 and is arranged substantially at right-angles to the arm 9 and extends from one side thereof in order that the roller 11 may have rolling contact with the cam 4 and be diametrically opposite the roller 8, although not in the same vertical plane therewith.

Above the rod 5 is a substantially flat disc shaped valve member 13, as commonly used in internal combustion engines of the character mentioned. The valve 13 has a depending stem 14 extending toward the rod 5 and in vertical alignment therewith. Arranged between the rod 5 and the valve stem 14 is a linking yoke 15. The valve stem 14 extends freely through the upper arm 16 of said yoke so that the stem may have vertical movement with respect thereto. The lower arm 17 of said yoke is connected with the upper end of the rod 5 by an adjusting screw 18 and a lock nut 19, as shown in Figs. 1 and 3 of the drawings. The lower end of the valve stem 14 is opposed to the adjusting screw 18 and, when the valve is closed, is out of contact therewith, as illustrated in Fig. 1.

On that portion of the valve stem 14 between the screw 18 and the upper arm 16 of the yoke 15 are two spring retainers 20, 21, vertically spaced apart by an interposed sleeve 22 surrounding the valve stem 14, as shown in Fig. 3. Each retainer 20, 21 has an outwardly extending annular flange 23. A light coiled spring 24 is arranged between these flanges 23, 23 and surrounds the spacing sleeve 22. The upper retainer 20 is loose on the valve stem and the spring 24 holds the same against the upper arm 16 of the yoke, while the lower retainer 21 is fixed to the valve stem by a cotter or other pin 21a, as shown.

The valve actuating mechanism shown and described operates as follows. When the shaft 1 is rotated by the engine, the cams 3 and 4 are revolved in unison. The cam 3 is shaped to open the valve 13 and the cam 4 is shaped to close the same; in addition both cams are shaped to allow the valve to remain open or closed for a predetermined period of time. When the parts are in the positions shown in Figs. 1 and 2, the valve 13 is closed. The cams are rotated in the direction indicated by the arrow *a* in Fig. 1.

As the opening face of the cam 3 moves under the roller 8, the rod 5 is raised carrying therewith the screw 18 and moving the same into contact with the lower end of the valve stem 14. At the same time the roller 11 moves from off of the high part of the cam 4 onto the joined closing face of the same. This permits the upward movement of the rod 5 to continue and the valve 13 is raised and lifted from its seat. During the time that the roller 8 is on the high part of the cam 3 the roller 11 is on the low part of the cam 4, thus holding the valve 13 open and permitting a greater quantity of explosive mixture to be drawn into the engine, when the valve is an inlet one, or allowing complete exhaust of exhaust gases from the engine cylinder when the valve is an exhaust one.

Being employed as a part of an explosive engine as used on automobiles, my valve mechanism operates in a heated condition due to the high temperatures developed in these engines. This causes the stem 14 to stick in its guide due to the expansion of the stem under such temperatures, and this condition causes the stem 14 to offer considerable or abnormal resistance to the movement of the stem in the opening and closing of the valve. Moreover, the high rate of speed at which these motors are usually operated makes it necessary to take into account the effect of inertia in a consideration of the operation of my device. My design contemplates these difficulties and was thought out on the basis that lighter parts could be used and heavy spring tension eliminated, all acting to the better performance of the engine.

Fig. 1 shows the relation of the parts when the valve 13 is fully closed or seated. Here, I wish to explain that it is mechanically impossible to have a puppet valve properly seated unless there is means furnished to take up the wear in the parts or inequalities that might develop, and this means in my design is through the spring 24. This spring, however, is light, as the design does not require heavy tension. However, the action of the spring 24 to be most effective requires that it be assembled slightly compressed and this is the condition of the spring when the valve 13 is fully closed or seated, as shown in Figs. 1 and 3. The sleeve 22 is of such

length that a slight clearance is allowed between it and the upper spring retainer 20, as shown in Fig. 3. The screw 18 is adjusted to allow a small clearance between itself and the valve stem 14 as shown. 70

In the first upward movement of the rod or member 5 from the position shown in Figs. 1 and 3, the rod takes up the clearance between the screw 18 and stem 14. At this time it is apparent that the clearance between the sleeve 22 and the upper spring retainer 20 has increased to the same extent as the clearance previously had between screw 18 and stem 14, and spring 24 has expanded to the same extent; or, in other words, the tension has been lightened somewhat. This same relation of the parts remains until rod 5 has been moved further upward and has opened the valve 13 to its greatest extent. This is the point where the abnormal conditions previously mentioned enter into the operation of the parts. 75

Taking into consideration the resistance offered to the closing of the valve and that the inertia of the parts has not been overcome by the spring 24, which I again emphasize is light and the tension of which has been further diminished in the upward movement, then the upper spring retainer 20 will come into contact with the sleeve or abutment 22 on the first downward movement of the rod 5 to close the valve. Because the valve 13 has remained inert, the screw 18 is taken out of contact with the stem 14, and the entire initial downward thrust will be delivered by this means in the closing of the valve as soon as the valve has started to move toward closing. As soon as the valve is put into motion, the spring 24 will again start to act and carry the downward thrust until the rod 5 reaches its lowest point. The clearance allowed between the screw 18 and stem 14 at this time would require that the spring 24 again compress slightly and hold the valve 13 seated. 105

The momentum of the valve when put in motion helps to close the valve and also helps to overcome the resistance offered to the closing of the valve by the latter sticking on its guide, thereby requiring the use of a very light spring 24. Moreover, this spring acts to hold the valve fully closed or seated and also to take up any irregularities produced in either the valve or the seat by expansion, carbon deposits or otherwise, and insures a proper and efficient closing of the valve. Moreover, the spring 24 holds the valve 13 fully closed in the interval of time between the effective contact of the rod and stem for opening the valve. This not only affords the use of a relatively light spring for fully closing the valve after the valve has been mechanically moved into initially closed position, but makes the use of a mechanism for mechanically opening and closing the valve 110 115 120 125 130

effective, due to the fact that the valve can be fully closed despite the variations that may exist in any of the parts of the structure as a whole or in the seating operation of the valve. The screw 18 is used to adjust any clearance needed in the structure to accommodate for any variations therein and allow the spring to properly close the valve.

In Figs. 5 and 6 I have shown a different form of cam means for opening and closing the valve. In said figures, 25 indicates a rod or member, similar to the one 5 and connected with a valve stem in the same manner as shown in the preceding figures. At the lower end of said rod 25 is a cross-pin 26, on which are journaled two rollers 27, 28, arranged on opposite sides of the rod 25, as shown in Fig. 6, and in the same horizontal plane. The roller 27 bears against the periphery of the cam members 29 fixed to the cam shaft 1^a and similar in shape to the cam 3 previously described. Also fixed to said shaft 1^a is a cam member 31 having an internal cam surface 32, against which the roller 28 bears and having substantially the same contour as the cam 4.

The form of cam means shown in Figs. 5 and 6 operates in substantially the same way as the cam means shown in the preceding figures, the cam 29 functioning to raise the valve from its seat and maintain it open a predetermined period of time, and the internal cam 31 functioning to close the valve and maintain it closed during a predetermined period of time; the only difference between the two forms of cam means described being in the arrangement of the construction whereby the rollers engage the cam members on the same side of the cams. In Figs. 5 and 6 it will be noted that both rollers are at the lower end of the rod 25 and are in the same horizontal plane, instead of being diametrically opposed as in the construction shown in Figs. 1 and 2.

The valve actuating mechanism, whether in the form shown in Figs. 1 and 2 or in the form shown in Figs. 5 and 6, causes a positive opening and closing of the valve by mechanical action, as distinguished from the spring action heretofore employed. Thus, all valve spring pressures are eliminated and the valve opened and closed and maintained in such positions by positive motor driven means. This construction makes possible the use of lighter parts because of the elimination of spring pressure for opening and closing the valve. Thus the amount of power required to operate the cam shaft is reduced and, furthermore, a quiet valve action is secured, in that the opening and closing of the valve is by mechanical means in both directions and all chattering or vibration of the valve is avoided. Furthermore, the construction described allows the use of cam contours not heretofore practicable because

the conventional design had to take into consideration the heavy spring pressures used for opening and closing the valve. The tendency of the cam follower to "ride" the cam at high speed is eliminated by my construction, and with this feature avoided it is possible to allow the valve to remain open longer and increase the power of the engine.

While I have shown and described herein in detail a valve actuating mechanism embodying the features of my invention, it is of course to be understood that the details of construction and arrangement of parts illustrated may be variously changed and modified without departing from the spirit and scope of my invention.

I claim as my invention:

1. A valve actuating mechanism, comprising in combination a valve with a stem, an endwise movable rod aligned with said stem and provided at its end with a member movable into and out of contact with said stem in the opening and closing of the valve, a yoke carried by said rod and slidably engaged with said stem, an abutment on the stem, an expansion coil spring about the stem and carried thereby between its lower end and the yoke, said spring being compressed by the yoke in its movement against said abutment so that the rod may close the valve against any resistance to its closing movement, said rod and stem being out of contact at the end of the closing movement for expansion of the spring to fully close the valve, and means for reciprocating said rod, said contact member at the end of the rod having adjustable connection therewith for regulating the clearance between the rod and the stem in relation to the clearance provided between the abutment and co-operating portion of the yoke.

2. A valve actuating mechanism, comprising in combination a valve with a stem, a rod aligned with said stem and movable into and out of contact therewith in the opening and closing of the valve, a yoke carried by said rod and slidably engaged with said stem, an abutment on said stem, an expansion coil spring about the stem and carried thereby between its lower end and yoke, said spring being compressed by the yoke in its movement against the abutment so that the rod may close the valve, said rod and stem being out of contact at the end of the closing movement for the expansion of the spring to fully close the valve, two laterally spaced power driven cams, and rollers carried by said rod and respectively engaging said cams for moving the rod in opposite directions.

3. A valve actuating mechanism, comprising in combination a valve with a stem, a rod movable endwise into and out of contact with said stem in the opening and closing of the valve, upper and lower retainers

on said stem, with the upper retainer loose thereon and the lower retainer fixed thereto, a sleeve between said retainers, a yoke having one end secured to said rod and the other end slidably engaged with said stem beyond the upper retainer, an expansion coil spring between said retainers, two laterally spaced power driven cams, an arm secured to said rod and extending between

said cams, and two rollers respectively carried by said rod and arm and engaging said cams at diametrically opposed points for moving the rod in opposite directions.

In testimony that I claim the foregoing as my invention, I affix my signature this 29th day of July, A. D. 1921.

JOSEPH HOLLE.
